Specification for Design.

Patented Aug. 2, 1921.

Application filed January 10, 1920. Serial No. 350,710. Term of patent 14 years.

To all whom it may concern:

Be it known that I, HERBERT W. KUGLER, a citizen of the United States, residing at Princeton, in the county of Mercer, State of New Jersey, have invented a new, original, and ornamental Design for a Tire-Tread, of which the following is a specification, reference being had to the accompanying drawing, forming a part thereof.

Figure 1, is a plan view of a section of a tire showing the design for the tread thereon.

Fig. 2, is a partial transverse section taken on the line 2—2 of Fig. 1, looking in the direction of the arrow.

I claim as new—

The ornamental design for a tire tread as shown.

HERBERT W. KUGLER.
